UNITED STATES PATENT OFFICE.

DAVID MOSKOWITZ, OF BROOKLYN, NEW YORK.

DESIGN FOR A SADIRON HOLDER.

Application filed July 29, 1922. Serial No. 3,241. Term of patent 3½ years.

To all whom it may concern:

Be it known that I, DAVID MOSKOWITZ, a citizen of Russia, residing in the borough of Brooklyn, in the county of Kings, city and State of New York, have invented a new, original, and ornamental Design for a Sadiron Holder, of which the following is a specification, reference being had to the accompanying drawing, forming part thereof, in which—

Fig. 1 is a plan with the sides turned out, and

Fig. 2 is an elevation.

I claim:

The ornamental design for a sadiron holder, as shown.

DAVID MOSKOWITZ.
